United States Patent

Des. 239,720
Patented Apr. 27, 1976

239,720

FACEPLATE FOR A DATA SET HOUSING OR SIMILAR ARTICLE

James R. Stewart, San Jose, Calif., assignor to GTE
Lenkurt Incorporated, San Carlos, Calif.

Filed Oct. 7, 1974, Ser. No. 512,568

Term of patent 14 years

Int. Cl. D14—02

U.S. Cl. D26—5 R

Fig. 1

Fig. 2

Fig. 3

Fig. 4

FIG. 1 is a front-perspective view of a faceplate for a data set housing or similar article showing my new design; FIG. 2 is a front-elevation view thereof;

FIG. 3 is a left-side view thereof; and

FIG. 4 is a section view thereof, taken along lines 4-4 of FIG. 2.

The rear of the article is substantially plain and unornamented.

The undisclosed side of the faceplate is a mirror image of the side that is shown.

I claim:

The ornamental design for a faceplate for a data set housing or similar article, as shown and described.
